UNITED STATES PATENT OFFICE.

FRED M. OSBORN, OF LOS ANGELES, CALIFORNIA.

AIRCRAFT COLLECTING DEVICE.

Application filed November 9, 1926. Serial No. 147,369.

The present invention relates to an apparatus whereby an aircraft may pick up mail, packages, and the like from the ground without the necessity of landing. An apparatus of this nature is particularly useful in the air mail as mail may be picked up en route at different places.

An important object of the invention lies in the provision of a device of this nature with a structure that is simple yet thoroughly reliable and efficient when in use.

A still further very important object of the invention lies in the provision of a structure which will enable an aviator to guide the aircraft for picking up mail, packages, or the like without utilizing any great amount of skill.

With the above and other objects in view as will appear as the description proceeds, the invention resides in certain novel features of construction and in the combination and arrangement of parts as will be hereinafter more fully described and claimed.

In the drawing:

25 Figure 1 is a top plan view of the apparatus embodying the features of my invention.

Fig. 2 is a side elevation thereof,

Fig. 3 is an enlarged detail top plan view 30 of one end thereof,

Fig. 4 is an enlarged detail fragmentary side elevation of a portion of the device,

Fig. 5 is an end elevation showing the arm and slide hanger.

35 Referring to the drawing in detail it will be seen that the numerals 5 denote two elongated bars which are angularly disposed in relation to each other in spaced relation and are co-extensive being supported horizontally above the ground at their forward ends by legs 6 and intermediate their ends by legs 7. The bars 5 converge from their forward ends towards their rear ends and are spaced at their rear ends. Strong spring 40 clips 8 are fixed to the bars 5 as at 9 and incline upwardly and rearwardly and terminate in horizontal ends 10 having depending projections 11. An engaging member includes an arcuate bight portion 12 having 45 diverging arms 14 which are adapted to rest on the rear ends of the bars 5 and the portions 10 of the spring clips 9 are adapted to

engage the ends of these arms 14 with the projections 11 seated in suitable recesses in the upper surfaces thereof. Bars 15 are hinged to the arms 14 adjacent their extremities as is indicated at 16 and extend rearwardly terminating in ends 17 which are normally engaged with each other by means of springs 18 which are fixed to the arms 14 and are bent over upon themselves and exert pressure upon the bars 15. An arm 19 projects at an acute angle from the rear end of one of the bars 5. A slide member 20 is mounted thereon and is adapted to have engaged therewith a mail bag 21 or any other package, device, or the like. A chain 22 is engaged with the slide hanger 20 and is engaged about one of the arms 14 being held in place by a plate 23 which holds one end link of the chain in recesses 24.

The numeral 25 denotes a cable which is adapted to be suspended from an airplane when in flight and at its lower end has fixed thereto a ball 26 the radius of which is greater than the radius of the curvature of the arcuate bight 12. Considering Figs. 1 and 2 the airplane will be flying from left to right and the cable will enter between the guide bars 5, pass between the ends 17 of the bars 15 so that the ball will be caught between the arcuate bight 12 and the arms 14 will be snatched from the bars 5 and the slide hanger 20 will be snatched from the arm 19 because of the chain 22. Thus the device or the like attached to the hanger 20 may be hoisted up into the airplane.

It is thought that the construction, utility, and advantages of this invention will be readily understood by those skilled in this art without a more detailed description thereof. The present embodiment of the invention has been disclosed in detail merely by way of example since in actual practice it attains the features of advantage enumerated as desirable in the statement of the invention and the above description. It is apparent that changes in the details of construction, in the sizes, in the proportions of the parts, and in the combination and arrangement of parts, may be resorted to without departing from the spirit or scope of the invention as hereinafter claimed or sacrificing any of its advantages.

Having thus described my invention what I claim as new is:

An apparatus of the class described including a supporting structure comprising a pair of horizontal co-extensive plates and angularly disposed bars; an engaging member resting on the bars and including a pair of hinged bars projecting inwardly of the member, and spring means associated with

said pair of hinged bars to hold the extremities in abutment, and spring clips on the supporting structure projecting upwardly therefrom and having depending projections engaging in depressions formed in the engaging member. 10

In testimony whereof I affix my signature. 15

FRED M. OSBORN.
